UNITED STATES PATENT OFFICE.

EUGENE H. McGEE, OF CHICAGO, ILLINOIS, ASSIGNOR OF ONE-FOURTH TO F. L. BARCHARD AND ONE-FOURTH TO JAMES E. McCAFFERY, BOTH OF CHICAGO, ILLINOIS.

AUTOMATIC DISPLAY SIGN.

Application filed October 26, 1921, Serial No. 510,473.

To all whom it may concern:

Be it known that I, EUGENE H. McGEE, a citizen of the United States, and a resident of Chicago, Cook County, and State of Illinois, have invented certain new and useful Improvements in Automatic Display Signs, of which the following is declared to be a full, clear, and exact description.

This invention relates to automatic display signs, and its principal object is to provide a non-transparent, flexible sign strip or ribbon provided with transparent portions, as for instance, words, letters, characters or other display matter, which may be moved past a given space, whereby the information carried by the strip may be brought into view in regular succession. Another object is to provide automatically operating mechanism for unwinding the sign strip from a spool or drum, and for moving the sign strip past an exposure opening in one direction to bring the advertisements, legends or other information, contained on the sign strip, into view in regular succession, and for automatically rewinding it upon said spool or drum, and for repeating said operations indefinitely.

With these and other objects and advantages in view, this invention consists in a non-transparent, flexible strip or ribbon provided with transparent words, letters, characters, or pictures embracing advertisements, legends or other information, which may be successively brought into view at a given place.

It further consists in automatic means for moving a sign strip or ribbon across an exposure opening, to bring the information carried thereby, into view in regular succession, which automatic means embraces spools or drums upon which the sign strip or ribbon is wound, and mechanism for unwinding it upon the first spool or drum, and repeating such operation indefinitely. It further consists in the several novel features of construction, arrangement and combination of parts hereinafter fully described, and claimed.

The invention is clearly illustrated in the accompanying drawings, in which:

Fig. 1 is a front elevation of a display sign embodying a simple form of the pres-

ent invention; Fig. 2 is a horizontal section taken on line 2—2 of Fig. 1; Fig. 3 is a rear view of the device with the back wall thereof removed; Fig. 4 is a detail cross-section taken on line 4—4 of Fig. 2; Fig. 5 is a detail cross-section taken on line 5—5 of Fig. 3; Fig. 6 is a detail horizontal section taken on line 6—6 of Fig. 3; Fig. 7 is a perspective view of a certain clutch mechanism for one of the spools or drums; Fig. 8 is a detail face view of the sign strip, partly broken away and Fig. 9 is a detail vertical cross-section through the sign strip.

Referring to said drawings, which illustrates one embodiment of the invention, the reference character 10 designates a case or cabinet, preferably in the form of an elongated box, having a top 11, bottom 12, front 13, back 14 and ends 15, secured together in any suitable and substantial manner. A base portion 16 may be provided for the case is desired.

In the front wall 13 is formed an elongated exposure opening 17, behind which is a pane or sheet of glass 18 forming a window through which a portion of the sign strip or ribbon 19 is made visible.

The sign strip or ribbon 19 preferably comprises a non-transparent flexible body portion 20 (see Fig. 9) which is provided with transparent portions 21, formed to represent characters, such as letters or figures that form words or numbers, or said transparent portions may embrace pictures, or words and pictures or other information which it is desired to display. The transparent portions of the sign strip may be formed by cutting out the material or body of the strip, and a transparent strip 22 may be pasted, glued, sewed or otherwise secured to the rear face of the body portion to strengthen and reinforce it, especially at the margins of the cut-away portions.

Behind the exposure opening 17 is a reflector 23, which is supported from the case or cabinet in any suitable manner (as for instance, by posts or braces 24) (see Fig. 4), and in said reflector are a number of lamps 25, preferably of the incandescent electric type, which afford the necessary illumination for the sign strip.

The sign strip 19 is carried by two spools

or drums 26, 27, located adjacent the ends of the case, and in the operation of the device said strip is unwound from one spool and wound upon the other, to move the strip past the exposure opening, and thereby expose the information carried by the strip, through the exposure opening. Idle rollers 28 are journalled upon the case at places adjacent the rear face of the window beyond the exposure opening, and the strip 19 is trained around said rollers, and is thereby held in a flat condition behind the exposure opening.

The spools, or drums, are mounted on shafts 29, 30, which are journalled in bearing brackets 31 secured to the top and bottom of the case. In the form of the invention illustrated, the spool 26 is fast on its shaft 29, and the spool 27 is loosely mounted on its shaft 30, and supported thereon, as will appear later.

Motor operated mechanism is provided for rotating said shafts 29, 30, and therewith the spools, to wind the strip upon one spool and unwind it from the other, and for reversing the motion, and thereby rewind the strip on the spool from which it was unwound, and unwind it from the one upon which it was wound, and for repeating said operations indefinitely, and the mechanism illustrated for accomplishing this result will now be described.

Mounted on the bottom of the case, adjacent the spools are electric motors 33, 34, the shafts of which are geared to the shafts 29, 30, respectively, by speed reduction gearing, as will appear. The motor 33 is the rewind motor, that is to say, it rewinds the strip upon the spool 26 after it has been displayed, and the gearing between its motor shaft and the shaft 29, may comprise a bevel pinion 35 on the motor shaft and a bevel gear wheel 36 on the shaft 29, with which the bevel pinion 35 meshes. The ratio between the pinion and gearing is such that a comparatively slow movement is imparted to the shaft 29, as compared with that of the motor shaft. The motor 34 may be termed the winding motor, as its function is to slowly rotate the shaft 30 and spool 27, and thereby slowly move the film strip past the exposure opening to display the information contained on the strip. The speed reducing gearing between the motor shaft of the motor 34 and the shaft 30 may comprise a train of gearing, consisting of a bevel pinion 37 on the motor shaft, a bevel gear wheel 38, with which the bevel pinion 37 meshes, a spur pinion 39 fast with or integral with the bevel gear wheel 38, and a spur gear wheel 40 fast on the shaft 30. The spool 27 rests upon the spur gear wheel 40 and is supported thereby.

The bevel gear wheel 38 and spur pinion 39 are rotatively mounted on a post or standard 41 secured to the bottom 12. The

reduction in speed is sufficient to cause the shaft 30 to rotate slow enough that the matter on the strip may be read with ease while passing the exposure opening.

In order that the motor 34 may remain at rest while the rewind motor 33 is in action, a clutch mechanism is provided between the shaft 30 and spool 27 which will now be described. Slidably mounted on the shaft 30 is a clutch collar 42 which is non-rotatively held on the shaft by a pin 43 that enters grooves 44 in the upper face of the collar 42. Said clutch collar is arranged to clutch with a clutch collar 45 fast on the spool 27, and conveniently, the collar 42 may be formed with tongues 46 that are arranged to enter corresponding recesses 47 in the clutch collar 45, when in clutching engagement. When the spool 27 is rotated in a reverse direction, the clutch collars are automatically unclutched and held in unclutched condition.

The means for unclutching the clutch collars 42, 45, when the spool 27 is rotated in a direction to unwind the strip therefrom, may comprise clutch collar lifting cams 48 that engage with arms or projections 49 on the clutch collar 42. The cams 48 have inclined faces which are encountered by the arms 49, when the shaft 30 is rotated in a direction to unwind the strip from its spool. The arms are thereby caused to ride up the inclined faces of the cams, thereby raising the clutch collar 42, and permitting the spool to rotate without rotating the shaft 30, and motor 34. The cams 48 are movably supported, as for instance, they may be hingedly supported by plates 50 secured to the case, and stops 51 are provided for holding said cams against movement in one direction, while permitting free movement in the other direction. Looking at Fig. 7, it will be observed that the shaft 30 is free to rotate in the direction of the arrow, and that the arms 49 will, when the shaft is thus rotated, swing the cams upward and freely pass by them, but that when the shaft is rotated in the opposite direction, the arms will ride up the inclined faces of the cams and thereby raise the collar 42, thus unclutching it from the collar 45.

Fig. 3 shows the parts in a position occupied when the rewind motor has finished rewinding the strip or ribbon on the spool 26, and at the instant that the winding motor is set in action. Automatic means are provided for turning the electric current on to one motor and simultaneously turning it off the other one, and for reversing such action and said mechanism will now be described.

Adjacent the ends of the strip 19 are slots 52, 53, and in the cylindrical wall 54 of each drum is a slot 55 with which the slots of the strip register when the latter is wound on 130

the spool. Mounted adjacent each spool is a switch actuating arm 56 which is yieldingly held against the film strip, and has a shouldered end 57 that is arranged to track on the strip in line with the slots 52, 53, 55, and is drawn into the slots when they are exposed. The arrangement of the parts is such that when the slots are uncovered, the shouldered end 57 enters the slots, and the edge 58 of the slot 55 of the spool encounters the shoulder and draws the arm 56 forward and, if the momentum of the parts is sufficient the continual rotation of the spool will cause the shouldered end of the arm to be swung out of the slots and out of engagement with the edge 58, because of the curved path taken by said edge in passing the shouldered end. Two slots 52, 53, are preferably employed at each end of the strip, because the momentum may be sufficient to cause the spool to rotate after the current has been shut off the acting motor, and turned on the other one, and in such event, the spool is free to continue its rotation without causing any injury to any of the parts. By the time it has made one revolution after the current has been shut off, it has slowed down, and as the edge 58 engages the shouldered end 57, it draws the arm 56 forward against the action of a spring 78 and the latter causes a braking action on the spool, stops it and starts to rotate it in the reverse direction, thus aiding the associated motor, in a measure, in starting the reverse motion of the spool.

The motors 33, 34, are controlled from a switch 59, which is operated by the arms 56. The switch 59 is preferably in the form of a knife switch, the blade 60 of which makes alternate contact with two contact pieces 61, 62. The circuit for the motor 33 may be traced from the main conductors 63, 64, through the wires 65, 66, to one side of the switch 59, and the circuit for the motor 34 may be traced from the main conductors 63, 64, through the wires 67, 68, to the other side of the switch. The switch actuating arms 56 are connected to the knife blade 60 by wires, cables or other connections 69, 70. It is evident from the above that when the switch actuating arm at either spool is drawn forward, the knife blade is correspondingly moved in the same direction, thereby closing the circuit for the motor for that spool and opening the circuit for the other motor.

In order that the switch actuating arms 56 may move outward from the spools, as the roll thereon increases in diameter, the arms are pivotally supported on axes running parallel with the axes of the spools. Conveniently, the arms 56 are slidably mounted in guides 71, which guides are pivotally supported on posts 72, said pivotal connection between the guides and posts per-

mitting the arms 56 to move outwardly under the increasing diameter of the rolls and to move back as the diameters of the rolls decrease. The guides may be tubular in form, if desired, and may have centrally apertured heads 73 at one end, through which the arms 56 are guided.

The arms 56 are yieldingly held in contact with the rolls on the spools by weights 77 connected to the guides 71 by flexible connections, such as cords, cables or the like, which pass through eyes 79.

On the inner ends of the arms 56 are discs 74 to which are fastened the switch connections 69, 70, and the connections 75 to the springs 78.

As it is desirable to have the lamps 25 illuminate the sign while the strip is passing in the direction to display the information thereon, the lamps 25 may be wired to the lead wires 67, 68, of the motor 34.

In the operation of the device and assuming that the rewind motor is rotating the spool 26 to wind the strip thereon, when the slot 52 at the other end of the strip is uncovered, the shouldered end of the associated actuating arm 56 is drawn into the slot of the spool, the edge 55 of the slot encounters the shoulder and draws the arm 56 forward against the action of the spring 78, thereby closing the circuit to the motor 34 and opening the circuit to the rewind motor 33. If the momentum of the parts is sufficient, the spool 27 will continue to rotate until the slot 53 reaches the shouldered end of the arm 56, and the latter will again enter the slot and the spool will again draw the arm forward against the action of the spring 78, which then acts as a brake for the spool and starts it in a reverse direction—the motor 34 by this time also having started. During the rewinding of the strip, the clutch mechanism has been inactive, but as soon as the motor 34 starts to rotate the spool shaft 30, the clutch collar 42 is disengaged from the cams and falls into clutching engagement with the clutch collar of the spool 27, thereby connecting it with the rotating shaft 30. The strip is thereby slowly wound on to the spool 27 and slowly moved past the exposure opening in the case until the slot 52 at the other end of the strip reaches the arm 56 at that end, whereupon the switch is thrown to close the circuit through the motor 33, and open the circuit through the motor 34.

As the spool 26 starts to rewind the strip thereon, the strip commences to rotate the shaft 30 in the reverse direction from which it was rotating, and the clutch collar is thereupon immediately unclutched from the collar 45 on the spool 27, thus permitting the motor 34 to remain at rest while the strip is being rewound on the spool 26.

While the sign is being displayed, the circuit is closed through the lamps 25, and the

sign is thereby illuminated, but when the current is shut off from the motor 34 while the strip is being rewound on the spool 26, the current through the lamps is also shut 5 off.

I claim as new and desire to secure by Letters Patent:

1. A display sign, comprising two spaced spools, a flexible display strip extending between said spools, and arranged to be wound thereon from one to the other and vice versa, the ends of said strip being secured to said spools, separate spool rotating mechanism for each spool, each including a motor and arranged to rotate one spool at a time in a direction to wind the strip thereon, and thereby unwind it from the other spool, and control mechanism for said motors, operating in conjunction with said strip to set the 20 motor in motion for that spool from which the strip is unwound.

2. A display sign, comprising a case having an exposure opening in one wall thereof, two spaced spools in said case, a flexible display strip extending between said spools behind said exposure opening and arranged to be wound thereon from one to the other and vice versa, the ends of said strip being secured to said spools, separate spool rotating mechanism for each spool, each including an electric motor and arranged to rotate one spool at a time in a direction to wind the strip thereon, and thereby unwind it from the other spool, and control mechanism for each motor, including an electric switch for each motor, operating in conjunction with said strip to close the switch to the motor for that spool from which the strip is unwound.

40 3. A display sign, comprising two spaced spools, each having a slot formed therein, a flexible display strip extending between said spools and arranged to be wound upon said spools from one to the other and vice versa, the ends of said strip being secured to said spools and the end portions of said strips having openings arranged to register with the slots in the spools, motor operated spool rotating mechanism for each spool arranged 45 to rotate one spool at a time in a direction to wind the strip thereon, and thereby unwind it from the other spool, and control mechanism for said spool rotating mechanism, embracing two actuating arms, each 50 engaging said strip and adapted to enter the slots in said strip and spool when they are uncovered, and co-acting with said spools when engaged thereby, to actuate the control mechanism, and set in motion the spool rotating mechanism for the spool which engages the actuating arm.

4. A display sign, comprising two spaced spools, a flexible display strip extending between said spools, and arranged to be wound 65 upon said spools, from one to the other and

vice versa, the ends of said strip being secured to said spools and there being slots in said strip adjacent its ends, electric motor operated spool rotating mechanism for each spool, arranged to rotate one spool at a time in a direction to wind the strip thereon, and thereby unwind it from the other spool, a motor switch and switch actuating mechanism having two switch actuating members, one for each spool and tracking on said strip in line with the slots on the end of the strip secured to the associated spool.

5. A display sign, comprising two spaced spools, each having a slot formed therein, a flexible display strip extending between said spools and arranged to be wound thereon from one to the other and vice versa, the ends of said strip being secured to said spools, and there being slots in said strip adjacent its ends arranged to register with the slots in the spools, motor operated spool rotating mechanism, and electric motor control mechanism embracing a switch and two switch actuating arms, there being one arm associated with each spool and having a shouldered part arranged to enter the associated slots when uncovered, an arm being arranged to be actuated by its associated spool when its shouldered part enters the notch therein, to thereby effect a closing of the switch.

6. A display sign, comprising two spaced spools, each having a slot formed therein, a flexible display strip extending between said spools and arranged to be wound thereon from one to the other and vice versa, the ends of said strip being secured to said spools, and there being slots in said strip adjacent its ends arranged to register with the slots in the spools, electric motors, one for each spool, gearing between each motor and its associated spool, a double contact switch, one side of which is in circuit with one motor and the other side in circuit with the other motor, two switch actuating arms, one associated with each spool and having a shouldered end arranged to enter the notch in the spool when uncovered, and engage with said spool, whereby said arm is moved by said spool in a direction to close the circuit through the motor associated with said spool.

7. In a display sign, two spaced spools, a display strip extending between said spools and arranged to be wound thereon from one to the other and vice versa, motor driven, speed reducing gearing for each spool, clutch mechanism between one spool and its associated gearing operating to clutch the spool to the gearing only when the latter is motor operated, and motor control mechanism cooperating with said strip to set in motion the motor for rotating the spool from which the strip is unwound.

8. In a display sign, two spaced spools, a

display strip extending between said spools arranged to be wound thereon from one to the other, and vice versa, motor driven gearing for each spool and clutch mechanism between one spool and its associated gearing, operating to clutch the spool to the gearing only when the latter motor is operated.

9. In a display sign, a non-transparent flexible strip, formed with cut-out portions forming display matter, and a transparent flexible backing strip adhesively secured thereto.

EUGENE H. McGEE.

Certificate of Correction.

It is hereby certified that Letters Patent No. 1,430,394, granted to Eugene H. McGee, of Chicago, Illinois, for an improvement in "Automatic Display Signs," were erroneously issued to the inventor, said McGee, and one-fourth to F. L. Barchard and one-fourth to James E. McCaffery, both of Chicago, Illinois, as assignees, whereas said Letters Patent should have been issued to the inventor, said McGee, and one-fourth to *James E. McCaffery and one-fourth to Albert J. Massow, both of Chicago, Illinois*, as shown by the records of assignments in this office; and that the said Letters Patent should be read with this correction therein that the same may conform to the record of the case in the Patent Office.

Signed and sealed this 7th day of November, A. D., 1922.

[SEAL.]

KARL FENNING,
Acting Commissioner of Patents.
